UNITED STATES PATENT OFFICE.

WILLIAM KROPFF, OF NEW YORK, N. Y.

DESIGN FOR A BOTTLE.

Application filed February 3, 1923. Serial No. 5,062. Term of patent 7 years.

To all whom it may concern:

Be it known that I, WILLIAM KROPFF, a citizen of the United States of America, and a resident of the borough of Manhattan, of the city of New York, in the county and State of New York, have invented a new, original, and ornamental Design for a Bottle, of which the following is a specification, reference being had to the accompanying drawing, forming part thereof.

The three figures of the drawings show my new design viewed from three points,

I claim:

The ornamental design for a bottle, as shown.

WILLIAM KROPFF.
